UNITED STATES PATENT OFFICE

CHESTER A. MACOMIC, OF CHICAGO, ILLINOIS, ASSIGNOR TO PATENT PRODUCT CORPORATION OF CHICAGO, OF WILMINGTON, DELAWARE, A CORPORATION OF DELAWARE

MATRIX STRIP FOR TYPE-CASTING MACHINES

Application filed November 1, 1928. Serial No. 316,600.

My invention relates to improvements in matrix and mat heads for type casting machines and the like and has for one object to provide an improved type of matrix wherein a pivoted or articulated locking and matrix propelling head may be associated with the matrix strip without increasing the effective thickness of the matrix strip and without sacrifice in strength or rigidity. 5 Another object is to provide a new and improved form of matrix strip. Other objects will appear from time to time throughout the specification and claims.

My invention is illustrated more or less diagrammatically in the accompanying drawings, wherein—

Figure 1 is a side elevation of a matrix strip and pivoted head showing the bed in section.

Figure 2 is a view similar to Figure 1 with the matrix head in the raised position.

Figure 3 is a section along the line 3—3 of Figure 1;

Figures 4 and 5 are views showing the 25 matrix strip and pivoted head disassembled.

Figure 6 is a section along the line 6—6 of Figure 5.

Figure 7 is a modified form with a printing strip substituted for a matrix strip.

30 A is a matrix strip. On its entire face, it is provided with a plurality of slots A¹, in the bottom of which are the characters to be cast by the strip. At both ends the strip is as at A² and A³ projected so that as the strip moves back and forth across the bed, the edges of the slots or the teeth between the slots dividing the separate impression points will be out of contact with the matrix bed and therefore not subject to wear or change.

40 A⁴ is a guide rib projecting upwardly from the back side of the matrix strip preferably of different material than the strip itself and dove-tailed or otherwise fastened thereto so as to associate with any suitable guiding means not here shown or illustrated for the purpose of properly positioning and guiding the matrix strip.

45 B is the matrix bed. It furnishes a flat metal strip upon which the matrix bed may ride. This bed is provided with a series of

serrations B¹ across the faces of which the matrix travels. These notches are so positioned with respect to the casting station that when the pivoted matrix head drops into any one of these notches the matrix is 55 properly locked in position so that it is correctly spaced longitudinally to make an impression.

C is the pivoted matrix head. It has a generally cylindrical boss C¹, whose axis is 60 perpendicular to the plane of the matrix and adapted to engage a cylindrical pocket C² in the matrix. C³ C⁴ are dove-tail arms extending downwardly from the pivoted head adapted to engage dove-tail pockets C⁵ 65 C⁶ in the matrix itself. C⁷ is a lug extending out from the end of the matrix strip adapted to engage the working tail C⁸ of the pivoted head. This tail has a lug C⁹ in opposition to the lug C⁷ and a tooth or claw C¹⁰ adapted 70 to engage selectively any one of these serrations or notches in the bed. C¹¹ is an operating or working tail adapted to be in engagement with any suitable mechanism for raising or lowering the head, such 75 mechanism not being here shown or illustrated. C¹² is a releasing tail at the forward end of the pivoted head which when depressed rotates the head as shown in Figure 2.

80 By this arrangement the pivoted head and matrix strip interlock. This interlocking is effected by engaging the cylindrical pivoted boss with its socket and swinging the pivot head into engagement with the two dove-tail 85 recesses as shown in Figures 1, 2 and 3, when all the parts are interlocked and held in position. In operation of the machine there is no pressure or load which can come upon the matrix head or the matrix strip tending to 90 disassociate these parts because as the matrices with their pivoted heads reciprocate back and forth into and out of casting position all stresses are longitudinal and no stresses tend to cause side-ways displacement 95 of the matrix strip with respect to the head. It will be noted that the head and the guide strip are thinner than the matrix strip and of the same thickness so that both the pivoted head and the guide strip may travel through 100

the guide or positioning means, thus permitting the matrix strips themselves to be pressed together without any interference by the guiding or operating members when an impression or cast is about to be made.

I have shown my invention as applied to a matrix strip and so referred to it in the specification and claims for purposes of convenience. It will, of course, be obvious that the same invention might be applied to a printing strip in which case instead of having the impression forming elements at the bottom of the pockets A¹, the pockets would become dividing pockets between the walls D and in this case the walls D would carry printing characters D¹ as shown in Figure 7. It will be understood therefore that in my claims where I refer to a matrix strip for type casting machines the language is used for purposes of illustration and convenience only and the claim is intended to be broad enough to cover either a matrix strip for a type casting machine or a type strip for a printing mechanism or other similar machine.

Moreover, it will be understood that the strip might be used instead of as a matrix strip or type bar as a rack to operate some other piece of machinery.

I claim:

1. A matrix for type casting machines and the like comprising a strip having a plurality of spaced recesses in one edge thereof, partition walls dividing said recesses, impression forming elements in the bottoms of said recesses, the opposed ends of the strips beyond the recessed area projecting downwardly beyond the partition walls, and a matrix bed upon which such strips travel with the downwardly projecting elements engaging such bed, the partition walls being held above it.

2. A matrix for type casting machines and the like comprising a matrix strip having impression forming elements therein, a guide strip projecting from the side of the matrix strip opposed to the impression forming elements, the guide strip being formed of different material from the matrix strip removably but rigidly mounted thereon and of lesser width than the matrix strip.

3. A matrix for type casting machines and the like comprising a matrix strip having impression forming elements therein, a guide strip projecting from the side of the matrix strip opposed to the impression forming elements, the guide strip being formed of different material from the matrix strip removably but rigidly mounted thereon and of lesser width than the matrix strip, the guide strip being dove-tailed into the matrix strip.

4. In combination with a matrix strip for type casting machines and the like, a pivoted actuating head associated with one end of the strip.

5. In combination with a matrix strip for type casting machines and the like, a pivoted

actuating head associated with one end of the strip, interlocking elements on the matrix strip and mat head adapted to limit their relative pivotal movement.

6. In combination with a matrix strip for type casting machines and the like, a pivoted mat head associated with one end of the strip, interlocking elements on the matrix strip and mat head adapted to limit their relative pivotal movement, said means comprising dove-tail notches in one and interlocking lugs in the other together with a pivot connection between them.

7. The combination with a matrix strip with an actuating head pivoted thereto and means for holding said head in the plane of said strip at all times.

8. The combination with a matrix strip with an actuating head pivoted thereto and means for holding said head in the plane of said strip at all times including interlocking members on head and strip.

9. The combination with a matrix strip with an actuating head pivoted thereto and means for holding said head in the plane of said strip at all times, including a dove-tail interlocking connection between head and strip.

10. In a type casting machine, a matrix strip, a mat head pivoted thereon, a locking claw projecting downwardly from the mat head and adapted selectively to be retracted above the bottom of the matrix strip and to project downwardly therebelow, a controlling finger projecting from the end of the mat head adjacent the claw, a seating pad projecting thereabove and a withdrawing finger projecting longitudinally on the other end of the mat head.

11. A matrix for type casting machine and the like comprising a strip having a plurality of spaced characters on the lower edge thereof, the opposed ends of the strip on either side of the group of characters projecting downwardly beyond the surface in which the characters are located.

12. The combination with a matrix strip of an actuating head pivoted thereon and interlocking therewith.

13. The combination with a matrix strip of an actuating head pivoted thereon and interlocking therewith, the interlocking elements of matrix strip and mat head only being adapted to maintain the two parts in the same plane.

14. In a type casting machine a matrix strip, a mat head pivoted thereon, a locking claw projecting downwardly from the mat head and adapted selectively to be retracted above the bottom of the matrix strip and to project downwardly therebelow.

15. In a type casting machine a matrix strip, a mat head pivoted thereon, a locking claw projecting downwardly from the mat head and adapted selectively to be retracted

above the bottom of the matrix strip and to project downwardly therebelow, a controlling finger projecting from the end of the mat head adjacent the claw.

16. In a type casting machine a matrix strip, a mat head pivoted thereon, a locking claw projecting downwardly from the mat head and adapted selectively to be retracted above the bottom of the matrix strip and to project downwardly therebelow, a seating pad projecting from the mat head above the claw.

17. In a type casting machine a matrix strip, a mat head pivoted thereon, a locking claw projecting downwardly from the mat head and adapted selectively to be retracted above the bottom of the matrix strip and to project downwardly therebelow, a disengaging finger projecting longitudinally from the mat head on the side of the pivot point opposed to the claw.

18. A matrix for type casting machines and the like comprising a strip having a plurality of impression forming elements along one edge thereof, the ends of the strip beyond the area occupied by the impression forming elements projecting downwardly beyond them.

19. A matrix for type casting machines and the like comprising a matrix strip having impression forming elements along one edge thereof, a guide strip projecting from the opposed edge of the matrix strip, the matrix strip and guide strip being rigidly and permanently fastened together, and the guide strip of less width than the matrix strip.

20. In combination with a matrix strip for type casting machines and the like, a pivoted mat head associated with one end of the strip, interlocking elements on the matrix strip and mat head adapted to limit their relative pivotal movement, said means comprising a shoulder on the matrix strip and an extension on the mat head extending beyond the shoulder and a lug on such extension interlocking with the shoulder.

21. In combination with a matrix strip, an actuating head, a pivotal connection between the matrix strip and the actuating head and additional means for holding said head at all times in the plane of said strip.

22. In combination with a matrix strip, an actuating head, a pivotal connection between the matrix strip and the actuating head and additional means for holding said head at all times in the plane of said strip, including an unlocking connection between strip and head.

23. The combination with a matrix strip of an actuating head pivoted thereto intermediate its ends, said head including a portion extending above the top of the strip and an additional portion adapted to depend be-

neath the bottom of the strip, when the head reaches one limit of its rotation.

24. The combination with a matrix strip of an actuating head pivoted thereto and a locking member projecting downwardly from the mat head and adapted selectively to be retracted above the bottom of the matrix strip and to project downwardly therebelow.

25. The combination with a matrix strip of an actuating head pivoted thereto and lying in the plane of the matrix strip, said head including a portion overlying the upper edge of said strip and a portion extending beyond one end of said strip.

Signed at Chicago, county of Cook, and State of Illinois, this 18th day of October, 1928.
